UNITED STATES PATENT OFFICE.

BENJAMIN I. HUGHES, JR., JONATHAN AINSLEY DICKEY, AND ERWIN C. CATTS, OF ATLANTA, GEORGIA, ASSIGNEES TO LANHAM COTTON CULTIVATOR CO., OF ATLANTA, GEORGIA.

CULTIVATOR.

Application filed April 5, 1920. Serial No. 371,352.

To all whom it may concern:

Be it known that we, BENJAMIN I. HUGHES, Jr., JONATHAN A. DICKEY, and ERWIN C. CATTS, citizens of the United States, residing at Atlanta, in the county of Fulton, State of Georgia, have invented a new and useful Cultivator, of which the following is a specification.

This invention relates to cultivators and is more especially designed for use in the chopping and cultivation of cotton although it is to be understood that it is also useful in the cultivation of other plants, such as beets and the like.

One of the objects of the invention is to provide a machine of this character which, with little effort can be caused to maintain the chopping and cultivating elements in proper relation to the row being acted on, thus rendering the machine efficient in operation when used in connection with either a straight row or a row that is irregular.

Another object is to provide combined steering wheels and barring off disks which are under the constant control of the operator and which can also be utilized as gauges for regulating the depth of the cut made by the chopping device.

A still further object is to provide means whereby the barring off and chopping elements can be supported in elevated positions, thereby to permit the machine to be drawn from place to place without allowing said elements to come into contact with the ground.

A still further object is to provide steering and barring off mechanism which is compact, durable, and formed of few parts.

A still further object is to provide improved means for operating the chopping element, said means utilizing a leverage which gradually increases from the beginning of each stroke of the chopping element and exerts its greatest force as the chopping element enters and passes through the hill being cut.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the

invention shown can be made without departing from the spirit of the invention.

In the accompanying drawings the preferred form of the invention has been shown.

In said drawings—

Figure 1 is a side elevation of the machine, the near-wheel being removed and the axle shown in section.

Figure 2 is a plan view, parts being broken away.

Figure 3 is a vertical longitudinal section on line 3—3, Figure 2, the drive shaft being shown in elevation.

Figure 4 is a front elevation, the draft beam being shown in section.

Figure 5 is a front elevation of the barring off and gauge disks or wheels and the parts cooperating therewith, portions being broken away.

Figure 6 is a rear elevation of the chopping blade and the parts cooperating therewith.

Figure 7 is an enlarged section on line 7—7, Figure 5.

Figure 8 is a section through one of the handles and showing the support for the cut controlling lever, said lever being shown in section.

Figure 9 is a section on line 9—9, Figure 2.

Figure 10 is a section on line 10—10, Figure 2.

Figure 11 is a detail view showing a portion of a slightly modified structure.

Referring to the figures by characters of reference 1 designates the supporting wheels of the machine carrying an axle 2, said wheels being adjustable longitudinally along the axle to vary the distance between the wheels. Any suitable means may be provided for holding the wheels against longitudinal movement along the axle. On the axle are mounted side castings 3 connected by an upper yoke 4 and by a lower yoke 5, the upper yoke constituting a support for a draft beam 6. Angular arms 7 are extended forwardly from the sides of the yoke 4 and are connected by coiled springs 8 to upstanding fingers 9 extending from sleeves 10 journaled on the axle 2 close to the outer sides of the castings 3. An ear 11 is extended rearwardly from each of the sleeves 10 and is pivotally engaged by a yoke 12 formed at

the front end of a link 13 the rear end of which is likewise preferably provided with a yoke, as shown at 14. The two links 13 are disposed at the respective sides of the machine and are directly opposite each other, it being obvious that they are capable of lateral swinging about their pivotal connections with the ears 11 and that they are also capable of swinging upwardly and downwardly about the axis of rotation of the sleeves 10.

The yokes 14 are pivotally connected to ears 15 which are formed on or secured to the sides of a frame 16 from which upwardly and rearwardly inclined handles 17 extend, these handles being provided with suitable braces 18. The frame is provided with spaced cross strips 19 forming the front portion thereof, the inner ends of these strips being secured to opposite side portions of a guide yoke 20 upstanding at the center of the front portion of said frame and having its side arms parallel. In this yoke is mounted a slide 21 having upper and lower guide ears at each side thereof, as shown at 22, for engaging the side arms of the yoke 20. Extending rearwardly from this slide is a bearing 23 and another bearing 24 extends forwardly from the slide, the bearing 23 being joined to the slide by forwardly diverging arms 25. A chopper shaft 26 is journaled in the bearings 23 and 24 and is also journaled in a bearing 27 carried by the yoke 20 hereinbefore referred to, there being universal joints 28 in the shaft 26 in line with the front and rear pivots respectively of the side links 13. This will be apparent by referring particularly to Figure 2 of the drawings.

Secured to the shaft 26 between the slide 21 and the bearing 23 is a collar 29. This collar has outstanding ears 30 carrying a pivot pin 31.

The references cited against this application have been considered carefully. The machine covered by this application is the result of numerous steps and a gradual development and it has been found that the use of the disks 47 mounted and operated in the particular manner disclosed, is one of the most essential features of the machine inasmuch as when the machine is drawn forward over fields it is not necessary for the user to bother with the handles 17. Simply by grasping the handle 52 the disks can be turned so as to guide the machine along the row, these disks not only serving properly to support a portion of the weight of the machine by reason of their flanges 48 but also serving to bar off the row being chopped. The references do not appear to show or suggest such an arrangement. Gesche, for example, appears to show a ground wheel and a furrow wheel one of which can be turned by the rider. Weatherly shows two

casters which are not capable of barring off the row or of steering the machine. It is thought that neither of these references constitute good citations as far as the rejected claims are concerned and the said claims should accordingly receive favorable consideration. In order to more clearly distinguish the rejected claims from the cited art the following amendment is made.

A rod 32 is pivotally mounted on said pin 31 and is slidably mounted within a guide ear 33 carried by the upper portion of the slide 21. A coiled spring 34 is mounted on this rod and bears downwardly against the ears 30 and upwardly against the ear 33, thus to hold the ears 30 normally depressed in either of two positions. By referring to Figure 6 it will be noted that the ear 33 is in vertical alignment with the shaft 26 and that after the pivot 31 passes the dead center in either direction, the spring 34 by expanding will thrust against the ears 30 until the shaft 26 is rotated either to the position shown in Figure 6 or to the reverse position with the ears 30 extending upwardly toward the other side of the yoke 20.

Secured to the rear end of the shaft 26 is a collar 35 having a stem 36 extending radially therefrom in a downward direction and diametrically opposite the ears 30. This stem 36 is slidably engaged by a tubular extension 37 to the lower end of which is attached a two edged chopping hoe 38, it being understood that the extension 37 can be adjusted along the stem 36 so as to position the blade 38 or hoe 38 at any desired distance from the shaft 26.

The slide 21, under normal conditions, is supported by the lower portion of the yoke 20 but, if desired, the slide can be raised upon the yoke by means of an angular lifting lever 39 pivotally connected, as at 40 to one arm of the yoke 20 while the angle portion of the lever is connected by link 41 to the slide 21. Thus it will be seen that by swinging the lever 39 laterally the link 41 will be elevated and its point of connection with the lever will be moved past the dead center so that the slide 21 will thus be raised and held, as when it is desired to lift the shaft 26 and the parts cooperating therewith.

Extending forwardly from the slide 21 are wings 42 each of which has superposed bearing ears extending forwardly therefrom as shown at 43, said ears being spaced apart. Journaled within each pair of bearing ears 43 is a spindle 44 having a collar 45 adjustably secured thereto and located between the ears 43, thus to hold the spindle against longitudinal movement without, however, interfering with its rotation. The lower end of each spindle is preferably offset, as indicated at 46 and provided with a suitable bearing stud engaging a concavo-convex 130

disk 47 on the inner or convex surface of which is arranged a circular flange 48 concentric with the disk and usually spaced from the periphery thereof for a distance 5 of about two inches. This flange 48 can either be formed integral with or can be attached to the disk in any suitable manner. The two disks 47 are oppositely disposed, as shown particularly in Figure 5 and are 10 adapted to be moved with the spindles 44 when they are rotated.

Secured to the upper portion of each of the spindles 44 is an arm 49, these arms being parallel and being connected by a 15 cross strip 50 pivotally attached to them. Thus it will be seen that the two spindles will rotate in unison. One of the spindles 44 extends upwardly above its arm and has a rearwardly extending arm 51 secured to 20 it. To this arm is attached an elongated lever 52 which extends upwardly and rearwardly between the handles 17. Thus it will be seen that when the machine is moving forward the operator by swinging the lever 52 25 to the right or to the left can cause the spindles 44 to rotate together, thus to turn the wheels or disks 47 so that they will guide the rear portion of the machine or, in other words, will shift the frame 16 and 30 the parts carried thereby laterally in either direction relative to the axle 2 so as to follow any irregularities in the row of plants being acted on.

A bail 53 is hung from supporting loops 35 54 attached to the back portion of the frame 16 and has its free ends inturned, as indicated at 55 to form bearings for disks 56 which constitute fenders, these disks traveling along the ground close to and back of 40 the chopping hoe 38.

Extending over the frame 16 are some spring strips 57 attached to the frame by means of hook bolts 58, as shown in Figure 9. Other spring strips 59 are extended 45 under the frame 16 and attached thereto by hook bolts 60 as shown in Figure 10. These strips 57 and 59 have their back end portions turned downwardly and to the lower ends thereof are secured cultivating plows or 50 points 61 for loosening the soil between the rows while the machine is traveling forwardly astride the row being acted on. The fenders 56 are extended between these plows 61 and the row being acted on.

55 Secured to the axle 2 is a drive gear 62 constantly in mesh with another smaller gear 63 which is loosely mounted on a counter shaft 64 journaled in the upper portions of the castings 3. A clutch member 65 is 60 formed with or secured to the gear 63 and another clutch member 66 is feathered on the counter shaft 64 and is adapted to receive pressure from a spring 67 mounted on the counter shaft and bearing at one end 65 against a collar 68 secured to said counter

shaft. An actuating lever 69 is fulcrumed at its forward end on a rod 70 extending laterally and downwardly from the beam 6 and secured to this lever is a depending fork 71 which loosely engages the slidible 70 clutch member 66. The lever 69 is supported by a tongue 72 extending laterally from the beam 6 and provided with a depression 73 in which the lever 69 is adapted to rest while the clutches are out of engagement 75 with each other. When the lever 69 is disengaged from the depression 73, however, the spring 67 will automatically shift the clutch member 66 into engagement with the clutch member 65, thus to couple the gear 80 63 to the counter shaft 64 so that said counter shaft will be driven through the gears 62 and 63 from the rotating axle 2.

Secured to the counter shaft 64 is a bevel gear 74 which meshes with another bevel gear 75 secured to one end of a longitudinally extending shaft 76 journaled within a bearing 77 carried by one of the side castings 3. To the forward end of this shaft 76 is secured a disk 78 having a wrist pin 79 on 90 which is mounted a pitman 80. This pitman, in turn, is pivotally connected to a crank arm 81, secured to the front end of the shaft 26 and the wrist pin 79 is so disposed relative to the crank arm 81 that, during 95 each complete rotation of the disk 78, the crank arm 81 will be swung upwardly and downwardly through approximately 90°. As the wrist pin 79 begins to ascend from its lowermost point it pulls through the pitman 100 80 on the crank arm 81, the leverage gradually increasing until the crank arm has moved one-half of its distance at which time the leverage begins to decrease until the wrist pin 79 reaches its uppermost position. 105

As the wrist pin begins to descend the movement of the crank arm 81 is reversed the leverage gradually increasing until said crank arm has completed one-half of its movement after which the leverage begins to decrease. 110 In this connection it might be stated that the chopping hoe 38 is so mounted or connected to the shaft 26 that said hoe comes against the row of plants and chops through them at the time that the crank arm 81 is subjected to the greatest leverage. Consequently the machine is maintained at the highest efficiency because the greatest power is exerted at the time when most needed during the chopping operation. 115

It is to be understood that when the lever 69 is engaged in the recess 73 and its supporting tongue 72 so that the two clutch members 65 and 66 are disengaged, the machine can move forwardly without operating 120 the counter shaft 64 and the parts driven thereby. Furthermore, by lifting the slide 21 by means of the lever 39 the rear portion of shaft 26 will be elevated, thus raising the chopping hoe 38 some distance from the 125 130

1 ground and also lifting the disks 47 out of contact with the surface of the ground. With the parts thus positioned the machine can be moved from place to place without acting on 5 the soil. After the machine has been placed astride a row of plants to be chopped the lever 39 is shifted so as to lower the slide 21 and bring the disks 47 into contact with the ground at opposite sides of the row. These 10 disks will enter the soil until the flanges 48 come into contact with the surface thereof, said flanges acting as gauges to limit the downward movement of the shaft 26 and of the chopping blade carried thereby. Thus 15 should the surface of the ground be uneven the disk 47 will always be kept at the same depth because the flanges 48 will travel over the uneven surface and maintain the chopping blade or hoe 38 in proper relation to the 20 surface of the soil. Lever 69 is disengaged from its support so that the spring 67 will throw the clutch member 66 into engagement with the clutch member 65, thereby coupling the gear 63 to the counter shaft 64. 25 As the machine moves forward the axle 2 will drive through the gears 62 and 63, the counter shaft 64 and the gears 74 and 75 to the shaft 76 and its disk 78. Thus motion will be transmitted through the pitman 80 to the crank arm 81 and the shaft 26 will be rotated back and forth to produce a corresponding movement of the chopping hoe. As before explained the chopping hoe will start gradually and will reach its maximum 35 speed and force as it passes under the shaft 26 at which time it is chopping through the plants in the path thereof. The rear portion of the shaft 26 can be maintained above the row simply by manipulating the lever 52. 40 By means of this lever the disks 47 can be quickly turned to the right or to the left, thus shifting the entire frame 16 and the parts carried thereby so as to maintain them in proper position relative to the plants being 45 acted on. This guiding of the rear portion of the frame is effected with but little exertion and affords a very accurate control of the machine, insuring accurate chopping of the plants. As a matter of fact the machine 50 can be properly maintained in position relative to the row without taking hold of the handles 17 and simply by manipulating the lever 52.

As the machine moves forward the disks 55 47, which converge forwardly, will bar off the row as well as act as gauges and as steering wheels.

The springs 8 exert a constant pull upon the arms 9 thus to act as counter-balances 60 for the rear portion of the machine which can therefore be raised easily relative to the beam 6.

The links 13 allow the rear portion of the machine to swing laterally freely under the 65 guidance of the disks 47.

As shown in Figure 11 a means may be provided for positively raising the shaft of the chopping element and the disks 47 and holding them in raised position, this means being used ordinarily when the disks 47 are 70 not provided with the flanges 48. This adjusting means may be of any construction desired. For example a bell crank lever 82 can be mounted on one of the guides or arms of the yoke 20 and can be connected by a depending link 83 to the slide 21. A rod 84 can be extended from the other arm of the bell crank lever to a small lever mounted adjacent one of the grips on the handles 17 and which lever has been indicated at 85. By 75 providing a toothed segment 86 and a dog 87 for engaging the segment, the lever 85 can be locked in any position desired and with the slide 21 of the shaft carried thereby at a predetermined elevation relative to the 80 surface of the ground.

What is claimed is:

1. The combination with supporting wheels and a structure mounted for up and down and lateral swinging movement relative to the wheels, of a chopping element carried by said structure, means for transmitting movement to said element from the supporting wheels, and disks in front of the path of the chopping element, and means 95 operated by a person following the machine, for simultaneously shifting the disks to guide the chopping element and to bar off the row being chopped.

2. In a machine of the class described the 100 combination with a structure having supporting wheels connected to the front portion thereof, of a chopping element carried by said structure and driven by the wheels, supporting disks connected to the structure 105 in front of the path of the chopping element, and means operated by a person following the machine for simultaneously shifting the disks to guide the chopping element and to bar off the row being chopped.

3. In a machine of the class described the combination with a movably supported structure, of a chopping element, means operated by the forward movement of said structure for actuating the chopping element, supporting disks connected to said structure in front of the path of the chopping element, and means operated by a person following the machine for simultaneously shifting the disks to guide the chopping element and to bar off the row being 110 chopped.

4. The combination with a movably supported structure, a chopping element, and means operated by the movement of said 115 structure for actuating the chopping element, of laterally spaced barring off disks connected to said structure in front of the path of the chopping element, and means operated by a person following the ma- 120 130

chine for simultaneously rotating the disks about individual upwardly extending axes to deflect the structure laterally, and to maintain it in its course.

- 5 5. In a machine of the class described the combination with a movably supported structure flexible laterally, a chopping element carried by one end portion of said structure, means operated by the forward movement of the machine for actuating the chopping element, of barring off disks connected to said end portion of the structure, means operated by a person following the machine for simultaneously rotating said disks about individual upwardly extending axes to bar off the row being chopped and to maintain said end portion of the structure and chopping element along its proper course irrespective of the position of the remaining portion of the structure.

6. In a machine of the class described the combination with a structure flexible laterally, and wheels for supporting the front end of said structure, of a chopping element carried by the rear portion of the structure, means operated by said wheels for actuating the chopping element, barring off disks connected to and supporting the rear portion of said structure, and means operated by a person following the machine for simultaneously rotating said disks to bar off the row being chopped and to maintain the rear portion of the structure in proper position relative to the row of plants and irrespective of the position of the front end of the structure.

7. The combination with a jointed structure flexible laterally and supporting wheels connected to the front end portion of said structure, of a chopping element carried by the rear portion of said structure, means for operating the chopping element, barring off disks connected to the rear portion of the structure and supporting the same, means under the control of a person following the machine for simultaneously rotating said disks about individual upwardly extending axes to bar off the row being chopped and to flex the structure laterally and maintain the chopping element and barring off disks in proper relation to the row of plants being acted on.

8. A machine of the class described including a movably mounted structure jointed for lateral flexing, a wheeled support for one end portion of the structure, a chopping element carried by the other end portion of the structure, combined gauge and steering disks supporting said end portion and in advance of the chopping element, and means operated by a person following the machine for simultaneously rotating said disks to maintain them in proper relation to the row being chopped and to bar off said row.

- 65 9. A machine of the class described in-

cluding a jointed structure mounted for lateral flexing, supporting wheels connected to the front end of said structure, a chopping element carried by the rear portion of the structure, combined gauge and barring off disks supporting the rear portion of the structure and in advance of the chopping element, and means under the control of a person following the machine for simultaneously rotating said disks, about upwardly extending axes to shift the rear portion of the structure laterally relative to the front portion, thereby to maintain the chopping element and disks in operative relation with a row of plants and to bar off said row. 80

10. The combination with a jointed structure mounted for lateral flexing, and movable means for supporting the front end of the structure, of a chopping element carried by the rear portion of said structure, 85 barring off disks supporting the rear portion of said structure and in front of the path of the chopping element, inwardly extending circular flanges upon said disks for gauging the depth of the disks when projected into 90 the soil, and means operated by a person following the machine for simultaneously rotating the disks to maintain them and the chopping element in operative relation to the row of plants acted on and for barring off 95 the row being chopped.

11. In a machine of the class described the combination with a jointed structure mounted for lateral flexing, and wheels supporting the front end of said structure, of a 100 chopping element carried by the rear portion of the structure, barring off disks, stems connected thereto and adjustably and revolvably connected to the rear portion of the structure, a connection between the stems for 105 insuring simultaneously rotation thereof, and means operated by a person following the machine for actuating the stems to deflect the rear portion of the structure relative to the front portion, thereby to maintain the disks and the chopping element in 110 operative relation with the row of plants being acted on and to bar off the row.

12. The combination with a jointed structure mounted to flex laterally, supporting 115 means connected to the front end of the structure and a chopping element carried by the rear portion of the structure, of upwardly extending guiding means carried by the rear portion of the structure, a slide thereon, 120 means for raising and lowering the slide, spaced barring off disks, stems thereon journaled in the slide, a connection between the stems to insure simultaneous rotation thereof, and means for rotating the stems to shift 125 the disks and maintain them and the chopping element in operative relation with the row of plants being acted on.

13. The combination with a jointed structure mounted for lateral flexing, support- 130

ing means for the front end of the structure, and a flexible shaft carried by said structure, and an upstanding guide upon the rear portion of the structure, a slide mounted thereon and constituting a bearing for the shaft, a chopping element carried by the shaft, combined barring off and steering disks, spindles extending therefrom and journaled within the slide, 10 means for rotating the spindles to shift the disks and maintain said disks and the chopping element in operative relation with the row of plants being acted on.

14. The combination with a jointed structure mounted for lateral flexing, supporting means for the front end of the structure, and a flexible shaft carried by said structure, of an upstanding guide upon the rear portion of the structure, a slide mounted thereon and 20 constituting a bearing for the shaft, a chopping element carried by the shaft, combined barring off and steering disks, spindles extending therefrom and journaled within the slide, means for rotating the spindles to shift 25 the disks and maintain said disks and the chopping element in operative relation with the row of plants being acted on and means for raising the slide upon the guide to elevate the chopping element and the disks relative 30 to the surface of the ground.

15. In a machine of the class described the combination with a wheel supported structure and an upstanding guide carried there-

by, of a slide engaging the guide, a shaft journaled in the slide, a chopping element 35 carried by the shaft, yieldable means carried by the slide for holding the chopping element normally at either of its two limits of movement, and means connected to the guide and slide for raising and lowering the guide 40 relative to the structure.

16. In a machine of the character described the combination with a wheel supported structure, a chopper shaft, a crank thereon, and a chopping element carried by 45 said shaft, of a drive crank, means for transmitting motion thereto from the supporting wheels, and a pitman connection between the cranks, said cranks and connection cooperating to impart a back and forth rotation to 50 the chopper shaft during each complete rotation of the drive crank, the power exerted by the drive crank increasing gradually until the chopping element is midway of each of its strokes and then gradually diminishing 55 to the end of each stroke.

In testimony that we claim the foregoing as our own, we have hereto affixed our signatures in the presence of two witnesses.
